UNITED STATES PATENT OFFICE.

THOMAS J. GREEN, OF CLOQUET, MINNESOTA.

DESIGN FOR A LAMP-GLOBE.

SPECIFICATION forming part of Design No. 35,141, dated October 1, 1901.

Application filed August 19, 1901. Serial No. 72,528. Term of patent 7 years.

To all whom it may concern:

Be it known that I, THOMAS J. GREEN, a citizen of the United States, residing at and whose post-office address is Cloquet, in the 5 county of Carlton and State of Minnesota, have invented and produced a new and original Design for a Lamp-Globe, of which the following is a specification, the construction being illustrated in the accompanying drawings, 10 in which—

Figure 1 is a view of a lamp-globe embodying my design. Fig. 2 is a sectional view therethrough. Fig. 3 is a top plan view, and Fig. 4 is a bottom plan view.

15 The essential features of my design for a lamp-globe are a hemispherical or dome-like body supported by a base annularly concaved, which latter merges into a cylindrical collar. Surmounting the hemispherical body 20 of the globe is a diametrically-reduced cylindrical orifice. A

Referring particularly to the drawings, A

represents the hemispherical part of the globe, flaring outwardly and downwardly, and is supported at its lower edge by the annularly- 25 curved base C, which latter is contracted inwardly and downwardly, projecting tangentially into the cylindrical collar D.

The top of the dome or hemispherical part of the globe is the cylindrical orifice B, which 30 in relation to the collar D is reduced considerably in diameter.

Having thus described my invention, what I claim as new, and desire to secure by Letters Patent, is—

35 The design for a lamp-globe as herein shown and described.

In testimony whereof I affix my signature in presence of two witnesses.

THOMAS J. GREEN.
